MILK SHAKE MACHINE

Joseph Biro, Chicago, Ill., assignor to Mills Industries, Incorporated, Chicago, Ill., a corporation of Illinois

Application September 22, 1954, Serial No. 32,395

Term of patent 7 years

(Cl. D2—3)

The figure is a front perspective view of a milk shake machine showing my new design. The opposite side of the machine is the same as the side shown and the back is unornamented.

I claim:

The ornamental design for a milk shake machine, as shown and described.
